UNITED STATES PATENT OFFICE

KARL A. WEBER, OF LOS ANGELES, CALIFORNIA

STORAGE AND DISPLAY CASE FOR FROZEN FOODS

Application filed February 18, 1930. Serial No. 429,275.

This invention relates to storage display cases, and is more particularly directed to a storage display case adapted to store and freeze, or maintain frozen, foods.

It is an object of this invention to provide a storage and display case for frozen foods which includes storage and display cabinets which may be kept at relatively low temperatures, and whereby foods may be maintained in the storage cabinet under freezing conditions and may be removed from the storage cabinets for the purpose of filling all orders.

Another object of this invention is to provide a cabinet which is divided into a storage and sales compartment and a display compartment and wherein means are provided for the maintaining of the storage and sales compartment at a considerably lower temperature.

Other objects and advantages of this invention it is believed will be apparent from the following detailed description of a preferred embodiment thereof as illustrated in the accompanying drawings.

In the drawings:

Figure 1 is a partial perspective end and sectional view of a device embodying my invention.

Figure 2 is a sectional side elevation thereof taken substantially on the line 2-2 of Figure 1.

Figure 3 is a sectional view of a modified form of storage and display case embodying my invention.

In the preferred embodiment of my invention illustrated in the accompanying drawings there is provided a cabinet which is divided into a storage compartment 1 and a display compartment 2. The cabinet is preferably formed of sheet metal forming the outer casing 3 within which cork 4 providing insulating material is positioned.

The forward portion of the display cabinet 2 is formed of transparent sections 5 and 6, each of which is constructed of a plurality of plates 7 of glass held apart to permit inspection of the meats disposed within the display section or compartment 2. Mounted within the display compartment 2 is a tray 8,

and a shelf 9 supported by brackets 10 may be provided above the tray 8 if desired. Doors 11 are provided for permitting access to the display compartment 2 when it is desired to place the foods on display. The doors 11 are, however, normally maintained closed and the foods displayed in the compartment 2 are not those which are to be sold, but may be samples thereof. The foods to be sold are stored and maintained at a temperature low enough to either freeze or maintain the foods frozen, and in the compartment 1 foods may be positioned in individual containers or cans 12, to which access may be had through doors 13 positioned over openings formed through the top plate 14 of the storage compartment 1 of the display cabinet. The cans 12 are likewise preferably provided with covers 15.

Means are provided within the cabinet for maintaining the requisite temperature within the storage and sales compartment 1 and within the storage and display compartment 2, which means are preferably as follows:

Formed within the compartment 1 is a brine container 16 which is substantially rectangular in end section and includes a side portion 17 which fits the back face of the compartment 1, the bottom section 18 which fits the bottom of the compartment 1, a forward section 19 which fits the front of the compartment 1, and all of which sections are in direct communication throughout their length. The forward section 19 terminates in a horizontal section 20, which extends throughout the length of the cabinet immediately below the tray 8. Projecting upwardly from the horizontal section 20, or the tray cooling section 20, is a forward rib section 21 and a rearward rib section 22, which likewise extend throughout the length of the cabinet and extend upwardly to provide a chamber within which the tray 8 is fitted. The tray 8 may be, and preferably is, divided into a plurality of independent sections which are fitted within the chamber thus formed.

A brine from any suitable or desirable source and of a temperature reduced sufficiently to maintain the requisite tempera-

ture in the compartment 1 is circulated through the sections 17, 18, 19, 20 and ribs 21 and 22 preferably as follows:

The brine is introduced into the rear section through a conduit 23 from any suitable or desirable cooling medium, the use of which is well understood in the art, and at a point near the top of the rear section 17. The cool brine then circulates down through the rear section 17 across through the lower section 18 and up through the front section 19 and into the horizontal or tray section 20 and passes from the tray section 20 up through the rearward rib 22 and passes back to the cooling medium through the recirculation conduit 24 which is preferably connected at the top of the rear rib 22.

The circulation thus maintained maintains the cooling compartment 1 at a temperature considerably lower than the temperature of the display cabinet 2 as the warmer brine is circulated through the horizontal section 20 and ribs 21 and 22.

It is preferable that the cabinet embodying my invention be divided into a plurality of sections by partitions 25 disposed within the storage and sales compartment 1, and that the cans 12 which contain the different foods be positioned within the individual compartments thus formed. The display compartment 2 is likewise divided into a plurality of sections each of which includes an individual tray 8 and to the rear of which there is provided a door 11 immediately above the door 13 of the individual sections of the storage compartment 1. In this manner the foods displayed in the individual rays 8 of the display section 2 are the same foods as are contained in the can 12 immediately below the said sections.

In the modified form of my invention illustrated in Figure 3 I have indicated similar parts with similar numerals with the addition of an exponent "a" thereto.

45. In this modification of my invention the entire display and storage sections are maintained within the enclosed case so that the doors 11^a through which access is had to the display compartment 2^a are enclosed within the storage and sales compartment 1^a, access being had to the display section 2^a through the doors 13^a and through the door 11^a. In this manner the entire structure may be retained at a lower temperature without permitting heat to flow into the structure as freely as when the doors 11 are opened in the modification illustrated in the Figures 1 and 2. In this structure it is intended that the food products which are to be sold are stored within the storage and sales compartment 1^a without utilizing the containers or cans 12.

Having fully described my invention, it is to be understood that I do not wish to be limited to the details herein set forth, but my

invention is of the full scope of the appended claims.

I claim:

1. A device of the class described comprising a refrigerated cabinet divided into a storage and sales compartment and a display compartment, including a partition within the cabinet dividing the same into the said compartment, and closure means within the storage and sales compartment mounted to open in the storage and sales compartment to gain access to the display compartment. 70

15. In a device of the class described, the combination of a cabinet, a partition within the cabinet for dividing the cabinet into a storage and sales compartment and a display compartment located at the front top portion of the cabinet, and doors in the partition and opening within the storage and sales compartment to allow access to the display compartment from the storage and sales compartment only. 75

20. Signed at Los Angeles, California, this 4th day of February, 1930.
